(57) **CLAIM**

The ornamental design for an automobile tire, as shown and described.

DESCRIPTION

FIG. 1 is a perspective view of an automobile tire showing the new design;

FIG. 2 is a front view of the automobile tire shown in FIG. 1, it being understood that the pattern repeats uniformly throughout the circumference of the tire;

FIG. 3 is a rear view of the automobile tire shown in FIG. 1; FIG. 4 is a left side view of the automobile tire shown in FIG. 1, which is the same as the right side view thereof; and,

FIG. 5 is an enlarged view showing a portion of the automobile tire shown in FIG. 2.
